Baldwin & Son

United States Patent Office.

H. A. M. HARRIS, OF PHILADELPHIA, PENNSYLVANIA.

Letters Patent No. 67,536, dated August 6, 1867.

IMPROVEMENT IN NEEDLES FOR SEWING MACHINES.

The Schedule referred to in these Letters Patent and making part of the same.

TO ALL WHOM IT MAY CONCERN:

Be it known that I, H. A. M. HARRIS, of the city and county of Philadelphia, in the State of Pennsylvania, have invented a certain new and useful Improvement in Sewing-Machine Needles, of which the following is a full, clear, and exact description, reference being had to the accompanying drawings, which make part of this specification, and in which—

Figure 1 is a side view of one of my finished double-pointed needles.

Figure 2 is a representation of the needle in its stock; and

Figure 3 is a top view of the needle-stock and screw-bolts with the hole drilled through it to receive and hold the needle.

It is the object of my invention to reduce the cost of sewing-machine needles without impairing their effectiveness; and to this end my invention consists in so forming the needle that one shank shall carry two points, having an eye in each point, so that when one point is worn or broken the reversal of the shank shall supply a new needle.

In manufacturing my needles I cut the steel wire of which they are to be formed of the length desired for the double-pointed needle A, point these lengths of wire at both ends *a* and *a'*, drill or punch an eye, *b* and *b'*, near each point, and punch or cut grooves *c* and *c'* on opposite sides of the eye for a length sufficient to retain the thread upon the needle the distance required to enable the thread to draw properly through the eye of the needle and the material being sewn. I then harden and polish the needle in any of the methods most approved, when the needle may be placed in its stock B properly, and is ready for use, one point being arranged for sewing while the other may be prevented from catching in the goods or injuring the operator by a shield, *d*, which may be slipped over the upper point of the needle and held in place by an elastic band, *e*, passing from the shield, to which it is attached by both ends, around the clamp screw-bolt *f*, by which the needle is held in place in the stock B. A hole, *g*, drilled through the screw-bolt may be made to receive the needle, and a screw-nut, *h*, on the opposite side of the needle-arm or stock B will draw the bolt and hold the needle securely in place, and when the screw-bolt *h* is relaxed the needle can be properly adjusted in every direction.

Needles thus constructed may be straight or curved, to suit a large variety of sewing machines, and may be of any size, and having two points to each stock they will prove extremely economical and be used with marked convenience.

What I claim as my invention, and desire to secure by Letters Patent, is—

The new article of manufacture, constructed substantially in the manner described, and constituting a double-eye pointed sewing-machine needle.

I also claim the combination with the double-eye pointed needle of a shield or cap, substantially as and for the purpose described.

In testimony whereof I have hereunto subscribed my name.

H. A. M. HARRIS.
